UNITED STATES PATENT OFFICE.

GEORGE O. BATELDER, OF MACOMB, ILLINOIS, ASSIGNOR OF ONE-HALF TO LAWRENCE BURKE, JR., OF MACOMB, ILLINOIS.

AUTO-EXTRACTOR.

1,229,864.

Specification of Letters Patent. Patented June 12, 1917.

Application filed March 20, 1917. Serial No. 156,144.

To all whom it may concern:

Be it known that I, GEORGE O. BATELDER, citizen of the United States, residing at Macomb, in the county of McDonough and State of Illinois, have invented new and useful Improvements in Auto-Extractors, of which the following is a specification.

This invention relates to cable winding drums, and more especially to those employed on a wheeled carrier such as an automobile and connected with power mechanism whereby the drum may be rotated to draw on a rope or chain and extract the vehicle from a rut or mud hole in which it has become stuck or stalled.

The primary object of the invention is to connect the drum with the front end of the crank shaft at the point where the engine is cranked, so that when the engine is started up the extractor mechanism will be operated without the necessity of throwing in the clutch and putting strain on the latter.

Another object is to avoid the use of any kind of clutch mechanism which would increase the parts and therefore the weight and expense of the sundry, because my invention is to be considered an attachment which is to be carried in the tool box and applied only when it is necessary for it to be used—therefore it comes under the head of motor vehicle sundries or accessories.

Other objects will appear from the following specification and claims, reference being had to the accompanying drawings wherein:

Figure 1 is a plan view of the front end of a motor vehicle with this attachment in place,

Fig. 2 is a front elevation of the same, and

Fig. 3 is a central longitudinal section, the chain or yoke and the block and tackle being omitted from Figs. 2 and 3.

Fig. 4 is a detail of the connecting shaft, and

Fig. 5 is a detail of the driving crank referred to hereinafter; while

Fig. 6 is a detail of one means for attaching the device to the frame.

In the drawings the letters W designate the front wheels of a motor vehicle, mounted on an axle A which underlies the springs S suitably connected to the frame bars F as usual. The latter support the engine whose main shaft M has a coupling C at its front end to receive the cranking handle when the engine is to be started; and R designates the radiator beneath which this handle is passed for this purpose. No novelty is claimed for the parts thus far described.

Coming now to the details of the present invention, the numeral 1 designates a steel rod or shaft detachably connected at its extremities by suitable means such as clips 2 to the frame bars F, and 3 is a yoke which by preference is a section of chain also detachably connected with said frame bars, possibly by means of the same clips as indicated in Fig. 6. Connected with the center of this yoke is a block-and-tackle mechanism 4 whose forward pulley block has a section of chain 5 capable of attachment at 6 to a stake driven in the ground or a tree or a fence post, or some object forward of the automobile or motor vehicle which we will understand is stuck in a rut or mud-hole in the road; and the rope 7 leads from said mechanism to the rear. Said rope leads over 80 and is wound on a drum 10 mounted loosely on the rod or shaft 1 between suitable thrust bearings 11 and carrying at one end a ring gear 12 which is in constant mesh with a driving pinion 13. The latter is fast on a short shaft section 14 connected by a universal joint 15 with another shaft 16 which is squared as shown at 17. Engaging the squared portion is a socket 18 of similar shape within a third shaft section 19—the whole 90 making up a driving shaft as best seen in Fig. 4. The rear end of the driving shaft is supported in the coupling C in a manner yet to be described, and its front portion is supported by a bearing 9 inclosing the front section 14, the bearing being carried at the center of an arch 8 whose arms are mounted on the shaft or rod 1. When now this driving

shaft is turned in the proper direction, motion is transmitted to the drum and the rope 7 is wound thereon; and it is obvious that when tension is imparted to the rope, 5 the block-and-tackle mechanism will cause the automobile or motor vehicle to be drawn out of the position where it is stalled. The primary object of the present invention is to rotate said driving shaft from the forward 10 or cranking end of the main shaft M of the motor vehicle instead of through its clutch mechanism or by any attachment which is indirectly connected with said main shaft as formerly.

15 I have employed the letter C to designate the coupling at the front end of the main shaft, into which the usual crank handle is inserted when the engine is to be started. I do not wish to be limited to the construction 20 of this coupling, and in fact my attachment is usually applied to motor vehicles which have a self-starter. But I prefer that the rearmost shaft section 19 as shown in Fig. 4 shall be provided with pins 25 or other means by which it can be connected with the coupling C when the attachment is put in place, and in order to hold it so connected I prefer to insert an expansive spring 21 within the socket 18 so 30 as to normally distend the shaft section 17 as will be clear. However, when the attachment is removed, or at times when it is not in use at all, the crank shown in Fig. 5 can be employed for starting the engine. This 35 crank is of ordinary construction excepting that its rear extremity 28 should be squared to fit the square socket 18. The interior of this socket while spoken of as being square, could of course have other angular configurations, and when the shaft section 17 is withdrawn and removed the squared extremity of the crank can readily be inserted therein as will be clearly understood. Or it might be possible to remove 40 the shaft section 19 along with the other sections of the driving shaft of this attachment, and shape the rear extremity of the crank to fit the coupling C as usual, but in that case the rear end of the shaft section 19 45 should be shaped to fit such coupling the same as does the crank handle.

When not in use this attachment is stored in the tool box or at some convenient place within the body of the motor vehicle. When 55 the latter becomes stalled in the roadway or elsewhere, the driver takes the attachment out of the tool box, and by means of the clips 2 fastens it to the frame bars F, connects the yoke and block-and-tackle mechanism, and leads the chain forward and attaches it to some permanent object at 6, while the rope 7 is left quite free but its rear end is brought back to and wound around 60 and attached to the drum 10. The telescopic shaft sections 17 and 19 are now engaged

with each other and the rear end of the section 19 with the coupling C, and then the engine is started. Revolving slowly at first, it soon picks up and its main shaft M imparts rotary motion to the driving shaft as shown in Fig. 4, and the latter through the pinion 13 imparts motion to the drum 10 and the rope 7 is wound thereon. The operator guides this rope in proper coils around the drum, and very soon it becomes taut; after which continued operation of the drum puts tension on the entire attachment and the motor vehicle is drawn out of place. The engine is then immediately stopped, the attachment disconnected and laid away, and the driver proceeds on his way. Attention is invited to the point previously made in this specification, which is that the driving shaft connecting the drum with the engine does not lead through the clutch mechanism 70 or through any devices or means indirectly connected with the main shaft M. The use 75 of the universal joint 15 is only to cause the forward shaft section to be deflected a little, as usually are the front ends of the frame 80 bars F, and it is necessary when the clips 2 are attached to said frame bars near their front ends and in order to give room between the main shaft 1 and the coupling C 85 for the interposition of the driving shaft 90 shown in Fig. 4. The telescopic connection between the shaft sections 17 and 19 is necessary to permit the insertion of the device after the main shaft 1 has been attached to the frame bars, and the detachable connection 95 of the shaft section 19 with the coupling C is necessary in order that when it is not employed the crank handle of Fig. 5 100 may be used. The parts are preferably entirely of metal excepting the block-and-tackle features, and further details need not 105 be amplified.

What is claimed as new is:—

1. In an automobile extractor, the combination with a rope, a winding drum therefor, a rod on which the drum is rotatably mounted, detachable connections between said rod and the frame bars of the motor vehicle, and an arch whose ends embrace said rod and whose center has a bearing; 110 of a beveled gear on said drum, a driving shaft mounted near its front end in said bearing and having a pinion engaging said gear, its body being in three sections, a universal joint between two of said sections, 115 a telescopic connection between two other said sections, means for normally distending these sections, and means for detachably connecting the rearmost section with the main shaft of the engine of the motor vehicle. 120
2. In an automobile extractor, the combination with a rope, a winding drum therefor, a rod on which the drum is rotatably mounted, detachable connections between 125 said rod and the frame bars of the motor vehicle.

vehicle, and an arch whose ends embrace said rod and whose center has a bearing; of a beveled driving gear on said drum, a driving shaft made in telescopic sections 5 and having one section mounted in said bearing, a pinion on this section engaging said beveled gear, a spring within the rear

section abutting against the end of the front section, and means at the rear end of the rear section for detachably connecting it 10 with the coupling at the front end of the main shaft of the motor vehicle engine.

In testimony whereof I affix my signature.
GEORGE O. BATCHELDER.
